UNITED STATES PATENT OFFICE.

JOHN HENRY LEGGE PATTERSON, OF TORONTO, ONTARIO, CANADA.

JACK.

Application filed October 22, 1925. Serial No. 64,150.

My invention, relating to a jack which can be attached to an automobile wheel and while attached will permit of the removal of the tire, comprises; a ram extensibly adjustable for engagement with the wheel hub, a base member having at one end ground engaging means, at the other end a head formed with an open sided socket for the ram axial to the length of the base member and which will enter between the brake drum and the felloe and bring the extensible ram in its contracted position into contact or nearly so with the wheel hub, and felloe engaging means interjacent the ground engaging means and head providing a wide engagement or bearing with the felloe at one side of the wheel; and is characterized by an adjustable clamp, engaging the felloe at the other side of the wheel, co-operating with the felloe engaging means for securing the jack to the wheel and completing the socket for the ram and the extensible adjustment of the ram to the wheel hub.

For an understanding of the invention reference is to be had to the following description and to the accompanying drawings in which:

Fig. 1, is a side elevation of the jack showing in dotted lines its attachment to an automobile wheel;

Fig. 2, is a vertical elevation at right angles to Fig. 1, showing the method of use;

Fig. 3, is a fragmentary perspective view, showing the jack head and the clamping means;

Fig. 4, is a perspective view of the jack head;

Fig. 5, is a side elevation of the clamping means;

Fig. 5^a is a perspective view of the clamping means looking from the opposite side to Fig. 3;

Fig. 6, is a perspective view of the ram

Fig. 7, is a fragmentary perspective view of a modification of the parts shown in Fig. 2;

Fig. 8, is a perspective view of a modification of the clamping means shown in Figs. 3, 4, and 5; and

Fig. 9, is a modification of the ram shown in Fig. 6.

Like characters of reference refer to like

parts throughout the specification and drawings.

The base member of the jack is adapted to be placed against the inner face of the wheel and comprises an arm 1 of a conformation corresponding to the curvature of the inflated tire. The upper end of this arm is of relatively considerable width or breadth and the top of its inner surface is formed with a rabbet 2 which has a wide bearing or engagement with the adjacent side and the inner perimeter of the felloe 3. At the lower end of the arm 1 is a ground engaging member 4 which may conveniently take the form of a plate, and at the upper end of the arm 1 is a head 40 of a height slightly less than the distance between the felloe and the hub 7. The head, transversely of the wheel, is relatively thin to enter between the felloe and brake drum and, in the preferred construction, consists of three perpendicular sides 8, 9 and 10 respectively. The sides 9 and 10 extend laterally from the side 8, and the three sides form a socket extending axially of the length of the base member, the fourth side of which is open. As shown in Figs. 1 to 4 inclusive, the edges of the sides 9 and 10 are inclined outwardly-upwardly from the bottom of the sides for a distance approximately two thirds the height of the head and then perpendicularly for the remainder of the height. In the sides 9 and 10 at the junction of the inclined and perpendicular parts of the edges are hinge sockets 11. The inner surfaces of the sides 9 and 10 are formed with serrations 13, and the serrations of the side 9 are staggered with relation to the serrations of the side 10, so that there will be a difference in height between the serrations on the two sides equal to one half their pitch. In the case of automobile wheels equipped with balloon tires, and in the case of automobile wheels with short spokes, there is very little space for the entry of the head between the brake drum and the felloe, and to meet conditions of this kind is one of the purposes of my present invention which is accomplished by constructing the jack with a relatively long thin head that can be introduced between the felloe and the brake drum. As a relatively thin head will not provide a socket for the reception of a ram

of sufficient strength to carry the load imposed by the supported vehicle, I have provided a removable part, adjustably connected to the head, to complete the socket for the ram. This part, hereinafter for convenience termed a clamp, consists of a plate 14 which, when the jack is assembled, is opposed to the side 8, and this plate has lateral projections or wings 15 the edges of which are opposed to the edges of the sides 9 and 10. As shown in Figs. 3 to 5^a inclusive, the wings 15 are formed with hinge members 16 corresponding to and entered in the sockets 11, and the inner face of the plate 14 is formed with an inclined surface 17 at the lower end of which is an outwardly inclined clamping member 19 for engaging the felloe at the outer side of the wheel. Extending through the plate 14 is a clamping bolt 20 the inner end of which engages in a screw-threaded hole 21 in the side 8. In order that the clamping member 19 may apply maximum pressure on the felloe 5 the bolt 20 is entered through the plate 14 at or near its lower extremity. This bolt when tightened forces the clamping member 19 against the felloe, and the latter then moves the head 40 in a radial direction towards the hub. This movement of the head increases the pressure exerted by the ram against the hub and the rabbeted surface 2 against the inner side of the felloe.

The felloe engaging surface of the clamping member 19 is undulating, with a central concave-convex part 22, and two convex parts 23 and 24 between the concave-convex part 22 and the edges of the clamping member. These convex parts 23 and 24 form two bearings for engaging the felloe without marring it when clamping pressure is applied. The rabbet is likewise formed with two curved bearings 50, for engaging the felloe and these in conjunction with the curved parts 23 and 24 provide four distinct contacts for the jack with the wheel. The ram comprises a shank 26, corresponding in cross section to the bore of the head 40. As shown in the drawings this shank 26, is substantially rectangular in cross section and its sides 27 and 28 which are in contact with the sides 9 and 10 of the head 40, have serrations for engagement with the serrations 13. The serrations of the side 27 are staggered with relation to the serrations of the side 28 so that the initial adjustment of the ram to the wheel hub can be effected within a distance of one half the pitch of the serrations, which adjustment is completed by the tightening of the clamping bolt 20. This tightening of the clamping bolt 20 causes the inclined member 19 to bear upon the felloe with sufficient pressure to force the entire jack radially toward the wheel hub. The inclination of the edges of the sides 9 and 10, when the hinge mem-

bers 16 are entered in the hinge sockets 11, permit of the rocking or swinging movement of the clamp relatively to the head during the tightening or slackening of the clamping bolt.

In Figs. 7 and 8, the head is shown to be much thinner than that shown in Figs. 1 to 5 inclusive, and the inner surface of the side 8 is formed with serrations 41. The inner surface of the plate 14 is formed with similar serrations 42, staggered with relation to the serrations 41. The ram shown in Fig. 9 comprises a shank, rectangular in cross section, the sides of which are serrated, with, the serrations 43 at one side staggered with respect to the serrations at the other side, so that the ram can be adjusted to the wheel hub within a distance of one half the pitch of the serrations, and the adjustment can be completed by tightening the clamping bolt against the clamp and the latter against the shank of the ram.

In the use of the jack, the base member is attached to the wheel by introducing the head between the felloe and the brake drum until the rabbet 2 comes into position to overlap the inner perimeter, and engage the inner side, of the felloe. In this position the curved arm of the base member is opposed to the inflated tire and the ground engaging means extends transversely to it. When the base member is properly positioned with respect to the wheel, the ram is entered in the socket of the head and the clamp is placed against the outer side of the ram and secured to the head by the clamping bolt. This maintains the assembly of the ram and base member, and the clamping bolt when tightened forces the inclined member 19 against the felloe at the outer side of the wheel, and draws the rabbet 2 of the base member tightly against the inner side. The continued tightening of the bolt causes the inclined member 19 to move the entire jack radially in the direction of the hub and force the ram tightly against it. If the ram is primarily adjusted to the wheel hub, within a distance of one half the pitch of the serrations, a slight tightening of the clamping bolt will complete the adjustment and secure the jack to the felloe. The jack is usually attached to the wheel at some convenient position between the ground and the horizontal diameter of the wheel, and the wheel when rotated brings the jack to a perpendicular position, which is a position parallel to the vertical axis of the wheel. When the jack comes to this position, the ground engaging member or plate forms a substantial contact with the surface upon which the jack is seated and the base member raises the wheel from the ground a distance corresponding to the space or interval between the inflated tire and the ground engaging member.

Having thus fully described my invention what I claim is new and desire to secure by Letters Patent is:—

1. A jack adapted to be secured to a wheel comprising a base member having ground engaging means at one end, a ram socket at the other end and felloe engaging means at one side of the base member interjacent the socket and the ground engaging means, in combination with an arm extensible in the socket, clamping means at the opposite side of the base member to the felloe engaging means, and means for adjustably connecting the clamping means to the base member for cooperating with the felloe engaging means in securing the jack to the wheel.

2. A jack comprising a base member, having ground engaging means at one end, an open sided socket for the ram at the other end, axial to the length of the base member, and felloe engaging means interjacent the socket and ground engaging means for contact with one side of the felloe, in combination with a ram entered in the socket and extensibly adjustable for engagement with the wheel hub, and clamping means at the opposite side coacting with the felloe engaging means for securing the jack to the wheel, said clamping means completing the socket for the ram.

3. A jack adapted to be secured to a wheel comprising a base member formed to allow of the removal of the tire while the jack is attached to the wheel, said base member having ground engaging means at one end, an open sided socket for the ram at the other end, and felloe engaging means between the socket and the ground engaging means for contact with the felloe at one side of the wheel, in combination with a ram extensible in the socket, means to complete the socket, a clamping member for engaging the felloe at the other side of the wheel, and means for tightening the clamping member against the felloe.

4. A jack, adapted to be secured to a wheel, comprising a base member formed to

allow the removal of the tire while the jack is attached to the wheel, said base member having ground engaging means at one end, an open sided socket for the ram at the other end, and felloe engaging means between the socket and the ground engaging means for contact with the felloe at one side of the wheel, in combination with a ram extensible in the socket, clamping means having a hinge connection with the socket, and means for tightening the clamping means to secure the jack to the wheel and complete the extensible adjustment of the ram.

5. A jack, adapted to be secured to a wheel, comprising a base member formed to allow the tire to be removed while the jack is attached to the wheel, said base member having ground engaging means at one end, a socket at the other end, and felloe engaging means between the socket and the ground engaging means for contact with the felloe at one side of the wheel, in combination with a ram extensible in the socket, clamping means cooperating with the felloe engaging means, having its inner surface inclined and having an inclined member at its lower end, engaging the felloe, securing the jack to the wheel and completing the extensible adjustment of the ram to the wheel hub.

6. A jack, adapted to be secured to a wheel, comprising a base member formed to allow the tire to be removed while the jack is attached to the wheel, said base member having ground engaging means at one end, a socket for the ram at the other end, and felloe engaging means between the socket and the ground engaging means for contact with the felloe at one side of the wheel, in combination with a ram extensible in the socket and clamping means for effecting the adjustment of the ram to the hub and cooperating with the felloe engaging means for securing the jack to the wheel, said clamping means, having a member with curved surfaces for contact with the felloe.

Signed at the said city of Toronto this twenty-fifth day of September, A. D. 1925.

JOHN HENRY LEGGE PATTERSON.
